UNITED STATES PATENT OFFICE

JAMES J. CONWAY, OF WEST HAVEN, CONNECTICUT, ASSIGNOR TO THE SEAMLESS RUBBER COMPANY, INC., OF NEW HAVEN, CONNECTICUT, A CORPORATION OF MASSACHUSETTS

DESIGN FOR RUBBER OR LIKE ARTICLE

Application filed February 7, 1931. Serial No. 38,581. Term of patent 14 years.

To all whom it may concern:

Be it known that I, JAMES J. CONWAY, a citizen of the United States, residing in West Haven, in the county of New Haven and State of Connecticut, have invented a new, original and ornamental Design for Rubber or Like Article, of which the following is a specification, when taken in connection with the accompanying drawing, in which is shown a face view of a piece of sheet rubber showing my new design.

I claim:

The ornamental design for rubber or like article substantially as shown.

JAMES J. CONWAY.
